UNITED STATES PATENT OFFICE.

WILLIAM H. EDWARDS, OF TERRE HAUTE, INDIANA.

DOOR-OPENER.

No. 919,141.

Specification of Letters Patent.

Patented April 20, 1909.

Application filed October 15, 1908. Serial No. 457,899.

To all whom it may concern:

Be it known that I, WILLIAM H. EDWARDS, a citizen of the United States, residing at Terre Haute, in the county of Vigo and State 5 of Indiana, have invented certain new and useful Improvements in Door-Openers; and I do declare the following to be a full, clear, and exact description of the invention, such as will enable others skilled in the art to 10 which it appertains to make and use the same.

This invention relates to improvements in door openers.

The object of the invention is to provide an 15 improved door opening mechanism adapted to be applied to any form of door whereby the latter may be automatically opened by the weight of a person approaching the same, and which will automatically close the same 20 after the weight of a person has been removed.

With this and other objects in view, the invention consists of certain novel features of construction, combination and arrangement of parts as will be described and particularly pointed out in the appended claims.

In the accompanying drawings, Figure 1 is a front view of a door showing the application of the operating mechanism thereto, 30 parts of the floor in front of the door and of the operating mechanism connected thereto being shown in section; Fig. 2 is a horizontal sectional view through the door casing immediately above the door showing a top plan 35 view of the operating mechanism; Fig. 3 is a vertical transverse sectional view through the floor and the hinged tread piece, showing the manner in which the latter engages and actuates the door-opening mechanism when 40 the weight is applied thereto; Fig. 4 is a rear view of the door showing the arrangement of the closing mechanism; and Fig. 5 is a detail perspective view of the door-opening lever.

Referring more particularly to the drawings, 45 1 denotes a door frame in which is hinged a swinging door, 2. In the floor or platform, 3, immediately in front of the door is formed a loose section or panel, 4, which is hinged at one end to the floor or platform 50 joists, 5, or to any part of the supporting structure or framework of the platform in such manner that the end of the panel adjacent to the free end of the door may move up and down. The loose panel, 4, is provided 55 with suitable cleats or other construction to prevent the same from warping, and the free

end of said panel rests upon and is normally held in an elevated position by means of a combined supporting and operating lever, 6, one end of which is suitably hinged to the 60 framework beneath the platform or floor, while the opposite end is connected to and supported by the lower end of a connecting rod, 7, the upper end of which has an adjustable connection with one end of a bell crank 65 lever, 8, by means of an eye-bolt, 9, which passes through a slot in the end of one of the arms of the bell crank lever and has applied to its upper end an adjusting nut 10, in the lower side of which is formed a V-shaped 70 notch, 12, which engages a V-shaped projection, 13, formed on the end of the bell crank lever, as shown. The engagement of the nut, 10, with the projection, 13, in the manner described, provides for a free rocking or pivotal 75 movement between these parts.

The bell crank lever, 8, is pivoted in a supporting bracket, 14, secured in suitable position on the side of the door frame near the upper end of the door, and in the upper arm 80 of the lever is formed a series of holes, 15, by means of which the outer end of an operating rod, 16, is adjustably connected to said lever. The opposite end of the operating rod is preferably threaded and said threaded end is 85 adapted to be screwed into a threaded socket, 17, the opposite end of which is preferably bifurcated, and is connected to one end of an operating lever, 18, which is pivotally mounted in a suitable bearing bracket, 19, secured 90 to the door frame adjacent to and above the hinged end of the door. The lever 18 is provided midway between its ends with oppositely projecting hubs or bosses, through which, and through the lever, is formed a 95 passage to receive the pivot pin of the lever, the ends of which are secured in the arms of the bracket, 19, whereby said lever is pivotally mounted in said bracket.

On the lower hub or boss of the lever 18 is 100 formed a right-angularly projecting door-opening arm, 20, on the outer end of which is pivoted an anti-friction roller, 21, which is engaged with a channeled bar or track-way, 22, secured to the upper end of the door, as 105 shown. On the outer end of the lever, 18, is formed a clevis, 23, with which is adjustably connected one end of a door-closing spring, 24, the opposite end of which is connected to the door frame above the door whereby 110 when the opening mechanism of the door is released said spring will automatically close

the door. In addition to the door-closing spring or to take the place of the same, if desired, I provide a supplemental closing mechanism consisting of a weight, 25, secured to 5 the end of a cord or cable, 26, which passes through guide pulleys, 27 and 28, secured to the door frame on the opposite side from which the opening mechanism is arranged. The inner end of the cord or cable, 26, after 10 passing through the guide pulleys, 27 and 28, is secured to the door, as shown at 29.

In the form of the invention herein shown and described the floor or platform supporting joists or sills are shown as running at 15 right-angles to the door and the loose panel 4 is shown as hingedly connected at one end to one of said joists. It will be understood, of course, that when the floor joists run in opposite directions or parallel with the door and 20 with the loose panel, a suitable construction will be provided to which said panel may be hinged and by which it is supported, and that when constructed in this manner, the combined lever, 6, will be constructed to provide 25 for this arrangement of the parts whereby said lever will operate in the proper manner. In the operation of the device, the loose panel, 4, is normally supported at one end by the lever 6 so that said end projects a suitable 30 distance above the floor or platform whereby when a person approaching the door steps upon said loose panel, his weight will depress the lever, 6, thus drawing down on the connecting rod, 7, and rocking the bell 35 crank lever, 8, which will draw upon the operating rod, 16, causing the latter to swing the operating lever, 18, and its door-opening arm in the proper direction to swing the door to an open position. After a person has 40 passed through the door and his weight is thereby removed from the loose panel, the closing spring, 24, or the weight, 25, or both said closing devices, will operate to retract the opening mechanism and thereby close the 45 door.

From the foregoing description, taken in connection with the accompanying drawing, the construction and operation of the invention will be readily understood without requiring a more extended explanation.

Various changes in the form, proportion and the minor details of construction may be

resorted to without departing from the principle or sacrificing any of the advantages of the invention as defined in the appended 55 claims.

Having thus described my invention, what I claim as new and desire to secure by Letters-Patent, is:

1. In a device of the character described, a 60 pivotally mounted door opening lever having a laterally projecting door opening arm, means whereby said arm is loosely engaged with the door, a longitudinal operating rod having one end adjustably connected with 65 one end of said lever, a bell crank lever having one arm connected to the opposite end of said operating lever, a pivoted platform adjacent to the door, a horizontally disposed pivoted lever adapted to support the free end 70 of the platform in elevated position, a vertically disposed connecting rod between the free end of the platform supporting lever and the other arm of the bell crank lever, and means whereby said door is automatically 75 closed when the free end of the platform is released.

2. In a device of the character described, a channeled track secured to the upper end of a door, a pivotally mounted door opening 80 lever having a horizontal door opening arm, a roller on the end of said arm to engage said track, an operating rod having one end adjustably connected with one end of said lever, a bell crank lever having one arm connected to the opposite end of said operating 85 rod, a pivoted platform adjacent to the door, a combined supporting and operating lever to normally hold the free end of said platform in elevated position, a connecting rod 90 between said lever and the other arm of the bell crank lever, a clevis on the outer end of the door opening lever, a spring connected at one end with said clevis and at its opposite end to the frame of the door, and a supplemental closing mechanism including a weight 95 arranged at the opposite side of the door.

In testimony whereof I have hereunto set my hand in presence of two subscribing witnesses.

WILLIAM H. EDWARDS.
